(57) **CLAIM**

The ornamental design for the cartridge dispenser, as shown and described.

DESCRIPTION

FIG. 1 is an upper front perspective view of a cartridge dispenser.

FIG. 2 is an upper rear perspective view thereof.

FIG. 3 is a top view thereof.

FIG. 4 is a bottom view thereof.

FIG. 5 is a side view thereof.

FIG. 6 is an opposed side view of FIG. 5.

FIG. 7 is a front view thereof; and,

FIG. 8 is a rear view thereof.

The broken lines in the figures illustrate portions of the cartridge dispenser and form no part of the claimed design.
